ANIMAL SNARE

Robert S. Connor, Little Marais, Minn.

Application May 29, 1946, Serial No. 672,997

6 Claims. (Cl. 43—87)

1

This invention relates to a novel construction of snare adapted for use in trapping and quickly killing large animals by hanging, so that the fur of the animal is not damaged and so that the suffering of the animal will be reduced to a minimum.

Among the principal objects of the invention is to provide an improved snare of the afore described character which will not be clogged by the fur or long hair of animals caught therein, which is equipped with a lock of sufficient size to afford play to a flexible member passing therethrough so that the snare will not be rendered inoperative by a kink in the flexible member and so that the flexible member will not be prematurely engaged by the lock and possibly broken or cut as a result thereof, and to provide a snare which will not be rendered inoperative by a coating of ice, sleet or rust.

Another object of the invention is to provide a snare which can be utilized an indefinite number of times and which is sufficiently durable and so constructed that it will not be damaged by use irrespective of the amount of pull exerted thereon by a captured animal.

Still a further aim of the invention is to provide a snare which can be set by a user while wearing heavy gloves this being advantageous since such devices are generally employed in very cold climates.

Other objects and advantages of the invention will hereinafter become more fully apparent from the following description of the drawing, which illustrates a preferred embodiment thereof, and wherein:

Figure 1 is a side elevational view showing the snare in an operative position;

Figure 2 is a fragmentary top plan view of a portion of the snare and on an enlarged scale;

Figure 3 is an enlarged longitudinal sectional view showing the snare lock in an operative position;

Figure 4 is a bottom plan view of the lock;

Figure 5 is an end view in elevation of the lock, looking toward the right-hand end of Figure 4, and

Figure 6 is an end view in elevation of the snare anchor.

Referring more particularly to the drawing, the numeral 7 designates the improved snare in

2

its entirety and which includes an elongated flexible member 8 which is preferably formed by a twisted, multi-strand cable, a lock designated generally 9 and an anchor member, designated generally 10.

The lock 9, as best illustrated in Figures 2, 3, 4 and 5 comprises a metallic member having a tubular end portion 11 which terminates at the free end thereof, in an outwardly flared flange 12. As best seen in Figures 3 and 4, the tubular portion 11 is provided with a V-shaped notch 13 which is disposed in the under part of the lock 9 and which opens outwardly of the flared rim 12 at its enlarged end. The edges or walls of the notch 13 are beveled from the outer side of the tubular portion 11 to provide sharpened edges 14 at the internal surface of the tubular portion 11, for a purpose which will hereinafter become apparent.

20 The opposite end of the lock 9 is formed by a pair of corresponding elongated arms 15 which are disposed at opposite sides of the lock 9 and which are formed integral with and extend from portions of the inner end of the tubular portion 11. The arms 15 are arcuate in cross-section and are tapered toward their free ends. The upper edges of the arms 15 are provided with a plurality of notches forming toothed or serrated surfaces 16. A pin 17 is disposed between and secured to the free ends of the arms 15 and has a sleeve 18 journaled thereon, between the arms 15.

25 The sleeve 18 is provided with an annular groove 19 adjacent one end thereof to receive the looped end 20 of the cable 8 which is formed by a clamp 21. The cable 8 is passed over the sleeve 18 and through the tubular portion 11 from its inner to its outer end. The inner end of the tubular portion 11 is beveled on its upper edge between the arms 15 to form a sharpened edge 22 beneath which the cable 8 extends. The opposite end of the cable 8 is passed through an eye 23 which is formed on one end of the anchor 10 and is turned back upon itself to form a loop which is held by a second clamp 21.

30 40 45 The anchor 10 is formed from a heavy strand of wire which includes a straight shank portion 24 which extends from the eye 23 and which terminates in a plurality of spaced coils 25 beyond which the strand is bent to form a plurality of folds 26 having parallel portions which are

spaced from one another. The opposite end of the strand forming the anchor 10 terminates in a laterally projecting terminal portion 27 having a flattened end, as best seen in Figure 6.

The flexible member or cable 8 may be of any length required and the end portion thereof, adjacent the anchor 10, is adapted to be looped around a tree trunk, limb, rock or any other suitable anchoring means and with the cable passed in and out between the folds of the portion 26 and the convolutions of the portion 25 for efficiently securing said cable end to the limb or rock or other anchoring means. It will thus be readily apparent that the anchor 10 affords an expedient means for fastening the end of the cable 8 which is connected to an anchoring means to avoid the necessity of tying the cable or flexible member 8 which is extremely difficult due to its relative rigidity. Further, the anchor 10 permits this tying to be accomplished while the user is wearing heavy gloves and without the removal thereof, which constitutes an important factor due to the fact that the snare 7 is commonly utilized in very cold climates, frequently under sub-zero weather conditions.

The portion of the flexible member or cable 8, between the ends secured to the sleeve 18 and the portion thereof disposed in the tubular portion 11, constitutes a noose 28 which is adapted to be positioned in a location where an animal will in likelihood pass its head therethrough. The noose 28 will be retained in any adjusted position to form a loop of any desired size due to the fact that the weight and normal tendency of the cable 8 to assume a substantially straight position will cause the lock 9 to swing to its position of Figures 1 and 3 so that the edge portions 14 and 22 will bite into the cable sufficiently to prevent sliding movement of the lock relatively thereto. The animal in passing its head into the noose or loop 28 will exert a pull thereon in a direction away from the interior thereof to cause the lock 9 to slide in a direction away from the anchor 10 thereby restricting the noose or loop 18 until it is disposed tightly around the animal's neck. The greater the pull exerted by the animal, the greater will be the amount that the loop or noose 28 is restricted so that a struggling animal will be quickly choked to death before it has an opportunity to damage its hide or fur and without enduring any prolonged suffering. It will also be readily apparent that when the noose 28 is tightened around the animal's neck the noose will tend to swing the lock 9 in a clockwise direction from its position of Figure 1 to cause the edges 14 and 22 to bite into the cable 8 and thereby effectively prevent slipping of the noose or loop 28. The serrated edges 16 will be disposed to engage the fur or hair of the entrapped animal to afford further means to prevent inadvertent disengagement of the lock 9.

In view of the size of the tubular portion 11 as compared to the cross-sectional size of the cable 8, it will be readily apparent that ice, sleet or rust will not prevent the operation of the snare 7 and including the lock 9 so that the snare will function even though it has been left exposed to the elements for a long period of time. Further, any hair or flesh becoming entangled in the lock 9 can be readily disengaged to permit the snare 7 to be reused an indefinite number of times. The internal diameter of the tubular portion 11 is made sufficiently large so that the snare will function even if the flexible member or cable 8 has become tangled or knotted.

Various modifications and changes are contemplated and may obviously be resorted to without departing from the spirit and scope of the invention as hereinafter defined by the appended claims.

I claim:

1. In a snare, an elongated flexible member, a lock having one end thereof connected to an end of the flexible member and provided with a tubular portion at its opposite end through which a portion of the flexible member loosely extends, said tubular portion being open at its ends and being of an internal diameter substantially greater than the diameter of the flexible member and less than the length of said tubular portion, said lock combining with a portion of the flexible member to form a loop or noose and being constructed and arranged whereby the tubular portion thereof will slide freely on the flexible member in a direction for restricting the size of the loop or noose, and means, forming a part of said tubular portion, to resist movement of the lock in the opposite direction relatively to the flexible member.
2. A snare as in claim 1, said means comprising a notch disposed lengthwise of said tubular portion and opening outwardly of the free end thereof for receiving and claiming a portion of the flexible member when the noose is restricted and tightly engaged about the neck of an animal.
3. A snare as in claim 1, said first mentioned end of the lock comprising laterally spaced arms connected at their free ends by a transversely disposed element, said portion of the cable extending over said transversely disposed element and said first mentioned end of the cable being connected thereto for rocking the lock toward a position transversely of said portion of the flexible member when the noose is engaged tightly about the neck of an animal.
4. A snare as in claim 1, said first mentioned end of the lock comprising laterally spaced arms connected at their free ends by a transversely disposed element, said portion of the cable extending over said transversely disposed element and said first mentioned end of the cable being connected thereto for rocking the lock toward a position transversely of said portion of the flexible member when the noose is engaged tightly about the neck of an animal, and said arms being provided with serrated upper edges adapted to engage the neck of an animal about which the noose is disposed.
5. A snare as in claim 1, said means comprising a notch disposed lengthwise of said tubular portion and opening outwardly of the free end thereof for receiving and clamping a portion of the flexible member when the noose is restricted and tightly engaged about the neck of an animal, said first mentioned end of the lock comprising laterally spaced arms connected at their free ends by a transversely disposed element, said portion of the cable extending over said transversely disposed element and said first mentioned end of the cable being connected thereto for rocking the lock toward a position transversely of said portion of the flexible member when the noose is engaged tightly about the neck of an animal, and said arms being provided with serrated upper edges adapted to engage the neck of an animal about which the noose is disposed.
6. In a snare, an elongated flexible member, a lock having one end thereof connected to an end of the flexible member and provided with a tubular portion at its opposite end through which

a portion of the flexible member loosely extends, said tubular portion being open at each of its ends, said lock combining with a portion of the flexible member to form a loop or noose and being constructed and arranged whereby the tubular portion will slide freely on the flexible member in a direction for restricting the size of the loop or noose, and said tubular portion having means forming a part thereof to resist movement of the lock in the opposite direction relatively to the flexible member.
